UNITED STATES PATENT OFFICE

106,591

DESIGN FOR A COMBINED STORE FRONT AND KNOCK-DOWN DISPLAY ROOM

William E. Doty and Donald P. Carmichael, Minneapolis, Minn., assignors to The Patty Cake Company, Minneapolis, Minn., a corporation of Minnesota

Application May 13, 1935, Serial No. 56,823

Term of patent 3½ years

To all whom it may concern:

Be it known that we, William E. Doty and Donald P. Carmichael, citizens of the United States of America, residing at Minneapolis, in the county of Hennepin and State of Minnesota, have invented a new, original, and ornamental Design for Combined Store Front and Knock-down Display Room, of which the following is a specification, reference being had to the accompanying drawings, forming part thereof.

Fig. 1 is an inside view of the knock-down display room as seen from the outside, front thereof with a portion of the front wall broken away; and

Fig. 2 is a front perspective view of the combined store front and knock-down display room.

The dominant features of this design reside in the upper half of the store front and interior portion illustrated in Fig. 1.

We claim:

The ornamental design for a combined store front and knock-down display room, as shown and described.

WILLIAM E. DOTY.
DONALD P. CARMICHAEL.
